This application is a continuation-in-part of my application for a patent filed on January 15, 1946, Serial No. 640,330, now pending, and is entitled "Shearing Machine".

UNITED STATES PATENT OFFICE

2,453,216

SHEARING MACHINE

Von B. Graham, Austin, Tex., and Kenneth E. Graham, Bedford, Ind.

Application April 8, 1947, Serial No. 740,106

13 Claims. (Cl. 125—23)

1

This invention relates to improvements in devices for shearing rock-like materials.

An object of this invention is to provide improved means for engaging and shearing stones and the like.

Another object of this invention is to provide means for resiliently biasing said shearing means.

A further object of this invention is to provide cam actuated locking means for securing said shearing means in a predetermined fixed position.

A further object of this invention means for actuating said cam means thereby retaining the blade of shearing position which follows the contour of the particular stone to be cut.

A further object of this invention is to provide an extremely efficient device of the character described which is capable of shearing stones in predetermined fixed lines with substantially no margin of error.

Other objects and features of novelty shall become apparent to those skilled in the art, in following the description of the preferred embodiment of the present invention, illustrated in the accompanying drawings, wherein—

Figure 1 is an elevational front view of the preferred form of the present invention;

Figure 2 is a transverse sectional view of the invention disclosed in Figure 1 and taken substantially on the line 2—2 thereof and in the direction of the arrows;

Figure 3 is an enlarged sectional detail of construction showing particularly the blade construction and locking means therefor;

Figure 4 is an enlarged fragmentary front view of a portion of the blade cutting means;

Figure 5 is a perspective view of a preferred blade to be used in conjunction with the present invention;

Figure 6 is a perspective view of the cam shaft utilized in the present invention;

Figure 7 is a sectional enlarged detail of construction showing a portion of the blade means forming part of the present invention;

Figure 8 is an enlarged fragmentary detail of construction showing primarily a portion of the bank of blades utilized in the present invention; and

Figure 9 is a longitudinal sectional view of the detail of construction shown in Figure 7 and taken substantially on the line 9—9 thereof and in the direction of the arrows.

Referring now in detail to the illustrated preferred embodiment of the present invention, like reference characters are used throughout to indicate similar elements thereof.

2

This invention has been developed to provide a device for improved operation of shearing devices, commonly used in various environments such as granite shearing, and the like. It is one of the

5 prime features of the present invention to provide an improved blade construction composed of a plurality of blade elements which follow the contour of the element to be sheared and then are locked in the contour following the position prior to shearing said rock or granite element.

A frame member, generally indicated by the reference numeral 10, is provided of conventional construction having the usual sides 12 and tie members 14 therein. Slots 16 are provided in

15 said sides 12 for the purpose of receiving the reciprocating slide member 18 therein. It is noted at this point that any conventional, suitable means for reciprocating the said slide member 18 may be employed in conjunction with the present invention. The bracket means 20, disclosed in Figure 1, is employed for connection between the power reciprocating means and the slide member 18.

20 A cross member 22 is provided beneath the said slide member 18 and may be rigidly secured to the said frame 10. By this arrangement of elements, an aperture is provided between the slide members 18 and cross 22 for the purpose of receiving stone and the like prior to and during cutting operation.

25 The slide member 18 has a receptacle 24 integral with the top portion thereof for receiving and seating springs 26 therein. It will be noted from an inspection of Figure 1 that a plurality of these receptacles 24 are provided along the upper edge of the said slide member 18.

The slide member 18 has a plurality of U-bolts 28 are provided at spaced intervals lengthwise of said slide member 18 and split bearings 30 are interposed between said U-clamps and the slide member 18. Brackets 32 are secured to a selected half of the split bearing means 30 by any suitable conventional medium such as screws 34, for the purpose of retaining a shaft 36 therein. The said shaft 36 receives an angle iron actuator 38 thereon for the purpose of transmitting motion from a cam projection to blades 40 to be described at this time.

30 Referring to Figures 5 and 6 there is seen a blade or chisel 40 having a protuberance 42 at one end thereof. Referring particularly to Figure 6 there is disclosed a cam shaft 45 having a plurality of eccentric cam lobes 46 thereon. The said cam shaft is journaled in the said split bearings 30, and protuberances 42 are secured to the said cam shaft at selected intervals along the axis

thereof. The blades 40 are slidably received between the slide member 18 and the actuator 38. It will be seen from an inspection of Figure 2 that a guide bar 50 is secured along the front portion of the said blade 40 to assist in slidably journaling the same. This guide bar 50 may be secured to the end split bearing members by any suitable conventional means, such as by utilizing brackets 52.

Flat surface terminal portions are provided on the cam shaft for the purpose of receiving actuator handles thereon. In operation the slide member 18 is rested on the stone to be sheared. The blades 40 are permitted to follow the detent and protuberances of the said stone. Then, the actuator handles 56 are pulled, turning the cam shaft and urging the lobe thereof against the tie bar 50. This, in turn, clamps the chisels or blades 40 against the flat surface of the slide member 18, holding the said blades in a predetermined fixed position, corresponding to the contour of the stone. After the stone is sheared, the handles are actuated in a reverse direction in order that the protuberance 48 may engage the right angular member 38. This, in turn, urges the chisels 40 upwardly against the force of the springs 26. Thus, the releasing operation is effected. In order to guide the said chisels further and to retain the springs 26 in the desired relative position, a reduced shank 60 is provided on each of the said chisels 40 for the purpose of sliding in and out of the receptacle 24.

It is noted at this point that an identical construction of chisels and actuating mechanism therefor, including locking means and resilient biasing means, is provided on the lower stationary cross member 22. In fact, the lower chisels and upper chisels cooperate following the general contour of the upper and lower surfaces of the stone to be cut. Since the lower chisel construction is identical to the upper construction, a detailed description is deemed unnecessary.

Reference is now made to Figures 7 to 9, inclusive, wherein a slight modification of the inventive concept is disclosed. It is seen that a pair of brackets 70 are secured to the slide plate 18 and a platform 72 is secured between said brackets. A plurality of fluid actuated pistons 74 are mounted on said platform and a bar 76 is secured to the terminal portion of each of the piston rods used in conjunction therewith. This bar 76 engages the chisels or blades 40 for the purpose of retaining the same in the desired adjusted position. Fluid pressure may be applied from any conventional exterior source and conducted through the conduit 78 to each of the said piston construction 74. This construction described above, takes the place of the cam locking means described in the first embodiment of the present invention.

The angle iron actuator 38 is rigidly secured to the shaft 80 and a handle means 82 is associated therewith for the purpose of actuating said actuator member 38. Any suitable means may be employed for journaling the said shaft 80 such as a pair of brackets 86 which are secured to the slide member 18. The operation of the chisel rocks contour following features of this embodiment of the present invention are identical to those features described hereinabove.

While there has been illustrated and described preferred embodiments of the present invention capable of performing all of the specifically mentioned objects as well as ancillary objects, it is apparent to those skilled in the art that various

changes including omissions and additions may be made herein without departing from the spirit of the invention. Accordingly, limitation is sought only in accordance with the scope of the following claims.

Having thus described the present invention, what is claimed as novel and improved is as follows:

1. In a device for shearing stone, a frame, slide members secured to said frame, blades slidably secured to said slide members, means for resiliently biasing each of said blades, means for locking said blades in predetermined fixed positions, means for actuating said locking means, means for lifting said blades, said lifting means and said locking means including a common cam shaft engageable with said blades.

2. In a device for shearing stone, a frame, slide members secured to said frame, blades slidably secured to said slide members, means for resiliently biasing each of said blades, means for locking said blades in predetermined fixed positions, means for actuating said locking means, said resilient biasing means including springs bearing on selected tie members and said blades, said locking means comprising rods having ellipsoidal cross sections journaled on said slide members.

3. The construction recited in claim 2, said locking means actuating means comprising handles extending from said rods.

4. A shearing apparatus comprising a frame, slide members secured to said frame, blades having protuberances thereon secured to said slide members, means for locking and lifting said blades in fixed positions, means for actuating said locking means, said locking means including cam rods journaled in said slide members engageable with said blades.

5. A shearing apparatus comprising a frame, slide members secured to said frame, blades having protuberances thereon secured to said slide members, means for locking and lifting said blades in fixed positions, means for actuating said locking means, said locking means including cam rods journaled in said slide members engageable with said blades, means for engaging said protuberances, means associated with said cam rods for lifting said engaging means.

6. A shearing apparatus comprising a frame, slide members secured to said frame, blades having protuberances thereon secured to said slide members, means for locking and lifting said blades in fixed positions, means for actuating said locking means, said locking means including cam rods journaled in said slide members engageable with said blades, means for engaging said protuberances, means associated with said cam rods for lifting said engaging means, spring means engaging said blades for normally biasing said blades on the surfaces of stone.

7. In a shearing apparatus, a frame, slide members secured to said frame, blades slidably secured to said slide members, common means for locking and lifting said blades, including a cam shaft journaled in said slide members engageable with said blades.

8. In a shearing apparatus, a frame, slide members secured to said frame, blades slidably secured to said slide members, common means for locking and lifting said blades, including a cam shaft journaled in said slide members engageable with said blades, protuberances on said blades, means for transmitting movement from said cam shaft to said protuberances during a

predetermined portion of the cycle of operation thereof.

9. In a shearing apparatus, a frame, slide members secured to said frame, blades slidably secured to said slide members, common means for locking and lifting said blades, including a cam shaft journaled in said slide members engageable with said blades, protuberances on said blades, means for transmitting movement from said cam shaft to said protuberances during a predetermined portion of the cycle of operation thereof, said transmitting means including a second protuberance on said cam shaft, and pivotal means for connecting said protuberances and said second protuberance.

10. In a shearing apparatus, a frame, slide members secured to said frame, blades slidably secured to said slide members, common means for locking and lifting said blades, including a cam shaft journaled in said slide members engageable with said blades, protuberances on said blades, means for transmitting movement from said cam shaft to said protuberances during a predetermined portion of the cycle of operation thereof, said transmitting means including a second protuberance on said cam shaft, and pivotal means for connecting said protuberances and said second protuberance.

11. In a shearing apparatus, a frame, slide members secured to said frame, blades slidably secured to said slide members, common means for locking and lifting said blades, including a cam shaft journaled in said slide members engageable with said blades, protuberances on said blades, means for transmitting movement from said cam shaft to said protuberances during a predetermined portion of the cycle of operation thereof, said transmitting means including a second protuberance on said cam shaft, and pivotal means for connecting said protuberances and said

second protuberance, spring means associated with said blades for resiliently biasing said blades to selected operative positions.

12. In a shearing apparatus, a frame, slide members secured to said frame, blades slidably secured to said slide members, common means for locking and lifting said blades, including a cam shaft journaled in said slide members engageable with said blades, protuberances on said blades, means for transmitting movement from said cam shaft to said protuberances during a predetermined portion of the cycle of operation thereof, means for actuating said cam shaft.

13. In a shearing apparatus, a frame, slide members secured to said frame, blades slidably secured to said slide members, common means for locking and lifting said blades, including a cam shaft journaled in said slide members engageable with said blades, protuberances on said blades, means for transmitting movement from said cam shaft to said protuberances during a predetermined portion of the cycle of operation thereof, said transmitting means including a second protuberance on said cam shaft, and pivotal means for connecting said protuberances and said second protuberance, and means for rotating said cam shaft.
